UNITED STATES PATENT OFFICE.

CHARLES P. WETMORE, OF MILWAUKEE, WISCONSIN, ASSIGNOR TO WETMORE REAMER COMPANY, OF MILWAUKEE, WISCONSIN, A CORPORATION OF WISCONSIN.

REAMER.

1,361,209.

Specification of Letters Patent.

Patented Dec. 7, 1920.

Application filed February 7, 1919. Serial No. 275,487.

To all whom it may concern:

Be it known that I, CHARLES P. WETMORE, a citizen of the United States, residing at Milwaukee, in the county of Milwaukee and 5 State of Wisconsin, have invented certain new and useful Improvements in Reamers, of which the following is a specification, reference being had to the accompanying drawing, forming a part thereof.

10 This invention relates to reamers having removable and adjustable blades.

The main objects of the invention are to provide for the renewal and adjustment of the blades to compensate for wear and sharpening and to vary the size of the holes reamed; to provide for reaming holes to the extreme closed ends thereof and truing the angles at the closed ends; to advance the ends of the blades as they are adjusted radially outward to compensate for wear and sharpening at the ends as well as the sides; to facilitate removing, replacing and adjusting the blades; to rigidly support the blades from end to end and to securely hold 20 them in place in the body of the reamer; to facilitate cutting by the blades and the removal of chips or cuttings; to provide for and facilitate the attachment of the reamer to various kinds of arbors, stems or spindles 25 for use in different machines; and generally to improve the construction and operation of reamers of this class.

The invention consists in the construction, arrangement and combination of parts 30 as hereinafter particularly described and pointed out in the claims.

In the accompanying drawing like characters designate the same parts in the several figures.

40 Figure 1 is a side elevation of a reamer embodying the invention and a part of an arbor with which it is detachably connected, the coupling sleeve being partially broken away; Fig. 2 is an end elevation as viewed 45 from the right relative to Fig. 1; Fig. 3 is a longitudinal section cutting opposite blade grooves in the body and showing blades inserted and secured therein; Fig. 4 is a similar section of the reamer body without the 50 blades, coupling sleeve and collars; and Fig. 5 is a side elevation of a blade.

The reamer comprises a cylindrical body 55 *a*, formed at one end with a reduced externally threaded shank *b*, and in the other end with an annular coaxial socket *c*, having its

outer wall threaded and its inner wall plain. It is also formed with longitudinal grooves *d*, the bottoms of which are inclined outwardly or away from its axis toward the socket *c*, as shown in Figs. 3 and 4. These 60 grooves, which in cross section are approximately radial to the axis of the reamer, are disposed obliquely thereto, receding or retreating relative to the direction of rotation for cutting toward the socket *c*, which they 65 intersect, as shown in Figs. 1 and 2.

Tapered blades *f*, removably fitted and adjustable lengthwise in the grooves *d* in engagement with the inclined bottoms thereof, are formed at their narrow or front ends 70 with internal undercut beveled notches *g*, approximately coinciding with the socket *c* when the blades are assembled in the body *a*, and are beveled at their back or wide ends 75 as shown at *h* in Figs. 3 and 5.

The faces of the blades adjacent to their front ends are concaved on one side next to their outer cutting edges, as shown at *j*, in Figs. 1 and 2, to form more acute angles and provide freer and better clearance for the 80 chips and cuttings along those portions of the blades which are subjected to the greatest duty.

A collar *l*, threaded on the shank *b*, is 85 formed on one side with an annular beveled face adapted to engage with the beveled back ends *h* of the blades, and a collar or nut *m*, externally threaded to engage with the internal thread in the outer wall of the socket *c*, is formed on one side with an annular beveled face adapted to engage with the undercut beveled ends or shoulders of the notches *g* in the front ends of the blades, as shown in Fig. 3. The blades are thus adjustably and firmly held in place in the 90 grooves *d* of the body, and may be simultaneously advanced lengthwise toward the front end of the body and thrust radially outward by the adjustment of the collars *l* and *m*, to compensate for wear and sharpening and to vary the size of holes reamed 95 therewith.

The collars are formed with slots *o* and *p*, as shown in Figs. 1, 2 and 3, to adjust them 100 with spanners for removing, replacing and adjusting the blades.

The threaded shank *b* of the reamer is provided with a coupling sleeve *r*, by means of which it may be readily and detachably fastened to arbors, stems or spindles of va- 110

rious kinds for use in different machines, a portion of a straight arbor *s*, to which the reamer is attached by the coupling sleeve, being shown in Fig. 1.

- 5 The body of the reamer is formed at the ends with countersunk center seats *u*, shown in Figs. 3 and 4, to facilitate its accurate formation with the blade grooves therein, and for accurately grinding, truing and 10 sharpening the outer cutting edges and front ends of the blades inserted and held therein.

The central part or solid boss of the body *a* in which the front seat *u* is formed, is flush with the annular end portion of the 15 body outside of the socket *c*, so that the seat is exposed and readily accessible to a center for grinding, truing or sharpening the blades when they are assembled and secured in place in the grooves *d*.

- 20 The oblique or inclined arrangement of the grooves *d* relative to the axis of the reamer, causes the blades to make a draw cut and to work easier and smoother.

The inclination of the bottoms of the 25 grooves *d* away from the axis of the body toward the socket *c*, with which they intersect at their front ends, causes the blades as they are adjusted radially outward to be advanced lengthwise toward and beyond the 30 front end of the body *a* so that as their outer edges are worn and ground away, their protruding front ends may be cut or ground away and trued to maintain true angles or corners between them and the longitudinal 35 cutting edges, for completely reaming holes and forming true angles or corners at their closed ends.

Along the grooves *d* next to the cutting sides of the blades *f*, the body *a* is grooved 40 or cut away, as shown at *w* in Figs. 1 and 2, to afford freer clearance for chips or cuttings.

As shown in Fig. 2, the front end of the body *a* and the front face of the collar *m* 45 are provided with an index and graduation marks to facilitate adjusting and setting the blades.

Various modifications in the minor details of construction and arrangement of 50 parts of the reamer may be made, without departure from the essential principle and scope of the invention as defined in the following claims.

I claim:

- 55 1. A reamer comprising a body formed with a reduced threaded shank at one end, a coaxial annular threaded socket and a central solid boss within the socket at the other end, and longitudinally grooves having bottoms inclined outwardly toward the socket; tapered blades of substantially uniform thickness fitting in said grooves against the inclined bottoms thereof and having beveled back ends and internal undercut beveled notches in the front ends;

and collars threaded on the shank and in the socket and having beveled faces adapted to engage the beveled ends and notches of the blades and to adjustably confine the blades in the body.

2. A reamer comprising a body formed with a threaded shank at one end, a coaxial annular threaded socket and a central boss within the socket at the other end, and obliquely disposed longitudinal grooves having bottoms inclined outwardly toward the socket; tapered blades of substantially uniform thickness fitting in said grooves against the inclined bottoms thereof and having beveled back ends and internal undercut beveled notches in the front ends; and collars threaded on the shank and in the socket, and having beveled faces adapted to engage the beveled ends and notches of the blades and confine the blades in the body.

3. A reamer comprising a body formed with a reduced externally threaded shank at one end, a coaxial annular socket having its outer wall threaded and a central boss within the socket at the other end, and longitudinal grooves of substantially uniform width having bottoms outwardly inclined toward the socket; tapered blades of substantially uniform thickness fitting in said grooves against the inclined bottoms thereof and having beveled back ends and internal undercut beveled notches in the front ends; and collars threaded on the shank and in the socket and having beveled faces adapted to engage the beveled ends and notches of the blades.

4. A reamer comprising a body formed with a threaded shank at one end, a coaxial annular threaded socket and a central boss within the socket at the other end, longitudinal grooves having their bottoms inclined outwardly from the axis of the reamer toward the socket; and center seats in the ends; tapered blades fitting in the grooves against the inclined bottoms thereof and having beveled back ends and internal undercut beveled notches in the front ends, and collars threaded on the shank and in the socket and having beveled annular faces adapted to engage the beveled ends and notches of the blades.

5. A reamer comprising a substantially cylindrical body formed with a threaded shank at one end, a coaxial annular socket and a central cylindrical boss within the socket at the other end, radiating longitudinal blade grooves and clearance grooves along the leading sides of the blade grooves, blades fitting in the blade grooves and having beveled back ends and internal undercut beveled notches in the front ends corresponding with the socket, the leading faces of the blades being concaved adjacent their front ends and forming sharp cutting edges.

at the sides, and collars threaded on the shank and in the socket and having beveled annular faces adapted to engage the beveled ends and notches of the blades.

- 5 6. A reamer comprising a body formed with a threaded shank at one end, an annular socket and a central cylindrical boss within the socket at the other end, and radiating longitudinal grooves having inclined
10 bottoms, tapered blades fitted in the grooves with their inner edges against the inclined bottoms thereof and having beveled back

ends and internal undercut beveled notches in the front ends, and collars threaded on the shank and in the socket and having beveled annular faces adapted to engage the beveled ends and notches of the blades, the exposed front end of the body and outer face of the front collar having index and graduation marks for predetermined adjustment of the blades. 15

In witness whereof I hereto affix my signature.

CHARLES P. WETMORE.
